DESIGN FOR A TOOTHBRUSH

Bernard Bernard and Bruno W. Kirschner,
New York, N. Y.

Application September 2, 1943, Serial No. 111,053

Term of patent 14 years

To all whom it may concern:

Be it known that we, Bernard Bernard and Bruno W. Kirschner, a citizen of Poland and a citizen of the United States of America, respectively, residing in the city of New York, county of New York, and State of New York, have invented a new, original, and ornamental Design for a Toothbrush, of which the following is a specification, reference being had to the accompanying drawing, forming part thereof.

Fig. 1 is a front perspective view of a toothbrush showing our new design.

Fig. 2 is a bottom plan view thereof.

The dominant feature of our design resides in the portions shown in solid lines.

We claim:

The ornamental design for a toothbrush, substantially as shown and described.

BERNARD BERNARD.
BRUNO W. KIRSCHNER.
